PISTON FOR ROCK DRILLS

Filed Oct. 8, 1928

UNITED STATES PATENT OFFICE

EARL B. LEAR, OF PHILLIPSBURG, NEW JERSEY, ASSIGNOR TO INGERSOLL-RAND COMPANY, OF JERSEY CITY, NEW JERSEY, A CORPORATION OF NEW JERSEY

PISTON FOR ROCK DRILLS

Application filed October 8, 1928. Serial No. 311,104.

This invention relates to rock drills, but more particularly to pistons for rock drills.

One object of this invention is to enable the operation of a rock drill with a water tube and with or without an air tube without changing the piston. Other objects will be in part obvious and in part pointed out hereinafter.

One embodiment of the invention is disclosed in the accompanying drawings, in which

Figure 1 is a longitudinal view of a rock drill, partly in section, showing both the air tube and the water tube in place.

Figure 2 is a view similar to Figure 1 but showing the interior of the drill with the air tube removed.

Referring more particularly to the drawings, 10 designates a rock drill having a cylinder 12 and a piston reciprocably mounted therein and adapted to strike against the shank end of a drill steel 32. As is customary, the drill steel 32 is hollow, being provided with a central bore 100 to receive a water tube 78 extending through a bore 40 in the piston coaxial with the piston. The bore 40 is sufficiently large to receive also an air tube 102 having a sliding fit in the bore 40 so as to prevent an excessive quantity of air from passing from the cylinder 12 through the bore 40. In this type of tool the tube 78 is connected with a source of supply of cleansing water under pressure which is mixed with air under full line pressure supply through the tube 102 which air supplies the force for driving the cuttings from the hole being drilled.

In many cases it is desirable, however, to omit the air supply tube 102 and usually this cannot be done unless the piston 22 is replaced with one of a smaller bore closely fitting the water tube 78. This invention provides means for permitting the same piston to be used under either condition. To this end the piston is provided with a tapered counter-bore 42 to receive a plug 104 adapted to be driven into the bore 42. Preferably the bore 42 is of somewhat greater length than the plug 104 and said plug is spaced from the smaller end of the bore to permit compensa-

tion for wear on the plug and the walls of the bore. The plug 104 is provided with a bore 106 of approximately the diameter of the tube 78 so as to prevent leakage of air between the tube and the plug. When it is desired to use the air tube 58 in addition to the water tube 78 the plug 104 is driven out and the piston is in readiness to receive both tubes 58 and 78.

In this instance the rock drill is of standard construction having a front head 16 and a front cylinder washer 18 interposed between the front head and the cylinder. A bore 20 in the front cylinder washer acts as a guide and centralizer for a reduced forward extension 22 on the piston 14, only a part of which is shown.

Ribs 24 on the piston extension 22 cooperate with flutes in a chuck nut 26 which is fixed in a chuck 28 by means of screw threads 30. These elements form part of the means for rotating a drill steel 32 and need not be described in greater detail since they form no part of this invention. The ratchet and pawl mechanism of the device is shown in part at 34.

A longitudinal central bore 36 in the piston 14 accommodates a rifle bar 38 which is only shown in part but which extends a substantial distance into the piston when the piston is in its rearwardmost position. A smaller cylindrical bore 40 is formed in the forward end of the piston extension 22 and a tapered bore 42 is formed between the bore 36 and the bore 40.

A back head 44 is secured to the cylinder 12 in a manner well known in the art. A throttle valve 46 having a handle 48 admits pressure fluid to or excludes pressure fluid from the chamber 50. A passage 52 conducts pressure fluid from the throttle valve to the chamber 50. Water for cleansing the drill hole is admitted to the back head through the hose 54.

A bore 56 is formed in the back head 44 to slidably receive the air tube 58. A flange 60 on the air tube 58 rests on a shoulder 62 which is formed at the juncture of the bore 56 and a larger bore 64. A plug 66 fits the bore 64 and rests on the flanged end of the

100

air tube 58. The plug 66 has a circumferential groove 68 from which radial passages 70 lead to a central aperture 72. A short passage 74 connects the chamber 50 to the groove 68. A packing member 76 through which extends the water tube 78 is placed on the plug 66 in the bore 64. A flange 80 on the water tube 78 rests on the packing member 76. A passage 82 leads from a chamber 84 in the back head 44 to a chamber 86 in which the water tube flange 80 rests. In order to secure the water tube 78, the packing member 76, the plug 66 and the air tube 58 firmly in place, a threaded plug 88 is screwed into a threaded aperture 90 in the back head and against the water tube flange 80. The plug 88 is provided with a hole 92 which receives the end of the water tube 78. A passage 94 leads from the hole 92 to the chamber 86 and a packing washer 96 is placed under the head 98 of the plug 88.

The operation of the tool as shown in Figure 1 and described above is as follows:

Assuming the rock drill to be in operation, water under pressure in the hose 54 enters the chamber 86 by way of the passage 82, it then enters the water tube 78 by way of the passage 94 and the hole 92. The water passes through the water tube and through a bore 100 in the drill steel 32, to the drill hole (not shown) where it cleanses the drill hole of rock particles. An additional cleansing and blowing effect is obtained by pressure fluid which passes from the chamber 50, through the passages 74 and 70 into a passage 102 between the exterior wall of the water tube 78 and the interior wall of the air tube 58. From the forward end of the air tube the pressure fluid passes into the drill steel bore 100 and assists the water in cleansing the hole being drilled.

As above referred to, under certain drilling conditions it is undesirable that pressure fluid be used as a cleansing medium and in cases of this kind it is an advantage to be able to remove the air tube and operate with water as the only means of removing the rock particles from the drill hole. When these conditions arise it is a simple matter to adapt a tool embodying this invention to the requirements above mentioned. The piston 14 is first removed from the cylinder and the tapered plug 104 driven into the tapered seat 42. The plug 88 is removed and the water tube 78, packing member 76, plug 66 and air tube 58 removed. The plug 66 is replaced by a plug 108 having a central bore 110. The packing member 76 is replaced, the piston returned to the cylinder and the water tube 78 inserted through the packing member 76, the bore 108 in the plug 110, through the bore 106 in the plug 104 and into the hollow drill steel 32.

The plug 104 effectually seals the interior of the piston against entry of water and also

acts as a guide and centralizer for the water tube. The plug 104 remains tightly seated due to the fact that each downward blow of the piston caused it to tend to seat more tightly. It is however, easily removed by inserting a rod through the aperture 40, after the water tube has been removed, and striking the rod a sharp hammer blow. As the passage 74 is sealed by the plug 110 it is impossible for pressure fluid to leak into parts of the drill where it is not desired.

I claim:

1. In a fluid actuated rock drill, the combination of a cylinder with a back head, a piston in the cylinder having a longitudinal bore therethrough, a recess in the back head coaxial with said bore, a passage in said back head for supplying pressure fluid to the recess, a water tube extending through the recess and the bore, removable means in the back head encircling the tube and seated in the recess to prevent entrance of pressure fluid into said recess, and removable means in the forward end of the piston encircling the tube and seated in the bore to prevent entrance of water into said bore.

2. In a fluid actuated rock drill, the combination of a cylinder with a back head, a piston in the cylinder having a longitudinal bore therethrough, a recess in the back head coaxial with said bore, a passage in said back head for supplying pressure fluid to the recess, a water tube extending through the recess and the bore, a plug in the back head encircling the tube and seated in the recess to prevent entrance of pressure fluid into said recess, and removable means in the forward end of the piston encircling the tube and seated in the bore to prevent entrance of water into said bore.

3. In a fluid actuated rock drill, the combination of a cylinder with a back head, a piston in the cylinder having a longitudinal bore therethrough, a recess in the back head coaxial with said bore, a passage in said back head for supplying pressure fluid to the recess, a water tube extending through the recess and the bore, removable means in the back head encircling the tube and seated in the recess to prevent the entrance of pressure fluid into said recess, and a tapered plug in the forward end of the piston encircling the tube and seated in the bore to prevent entrance of water into said bore.

4. In a fluid actuated rock drill, the combination of a cylinder with a back head, a piston in the cylinder having a longitudinal bore therethrough, a recess in the back head coaxial with said bore, a passage in said back head for supplying pressure fluid to the recess, a water tube extending through the recess and the bore, a plug in the back head encircling the tube and seated in the recess to prevent entrance of pressure fluid into said recess, and a tapered plug in the forward end

of the piston encircling the tube and seated in the bore to prevent entrance of water into said bore.

5. In a fluid actuated rock drill, the combination of a cylinder with a back head, a piston in the cylinder having a longitudinal bore therethrough, a tapered portion at the forward end of the bore, a recess in the back head coaxial with said bore, a passage in the back head for supplying pressure fluid to the recess, a water tube extending through the recess and the bore, a flange on the water tube adjacent the recess, a member threadedly engaging the back head and seated against one side of the flange, a plug in the back head encircling the tube and seated in the recess to prevent entrance of pressure fluid into said recess, a packing member between the plug and the flange on the water tube, said packing member and plug being secured in position by the pressure of the threaded member against the flange, and a tapered plug engaging the tapered portion of the piston bore and encircling the tube to prevent entrance of water into the bore, said tapered plug being constantly urged into closer engagement with the piston upon forward movement thereof.

20 In testimony whereof I have signed this specification.
